CLAIM

The ornamental design for a safe, as shown and described.

DESCRIPTION

FIG. 1 is a right, front perspective view of a safe showing our new design, in a closed configuration;
FIG. 2 is a front elevation view of the safe of FIG. 1;
FIG. 3 is a back elevation view of the safe of FIG. 1;
FIG. 4 is a right side elevation view of the safe of FIG. 1;
FIG. 5 is a left side elevation view of the safe of FIG. 1;
FIG. 6 is a top plan view of the safe of FIG. 1;
FIG. 7 is a bottom plan view of the safe of FIG. 1;
FIG. 8 is a right front perspective view of the safe of FIG. 1 in an open configuration;
FIG. 9 is a front elevation view of the safe of FIG. 8;
FIG. 10 is a back elevation view of the safe of FIG. 8;
FIG. 11 is a right side elevation view of the safe of FIG. 8;
FIG. 12 is a left side elevation view of the safe of FIG. 8;
FIG. 13 is a top plan view of the safe of FIG. 8; and,
FIG. 14 is a bottom plan view of the safe of FIG. 8.
The broken lines in the drawings depict portions of the safe that form no part of the claimed design.
